UNITED STATES PATENT OFFICE

150,020

DESIGN FOR A TOY ANIMAL FIGURE OR THE LIKE

Thomas C. Martin, Natick, Mass.

Application May 24, 1947, Serial No. 139,256

Term of patent 14 years

(Cl. D34—2)

To all whom it may concern:

Be it known that I, Thomas C. Martin, a citizen of the United States, residing in Natick, in the county of Middlesex and State of Massachusetts, have invented a new, original, and ornamental Design for a Toy Animal Figure or the like, of which the following is a specification, reference being had to the accompanying drawing, forming a part thereof, in which

I claim:

The ornamental design for a toy animal figure or the like, as shown.

THOMAS C. MARTIN.
